UNITED STATES PATENT OFFICE.

JACOB DREISÖRNER, OF NEW YORK, N. Y.

IMPROVEMENT IN HYDRAULIC ENGINES.

Specification forming part of Letters Patent No. 57,298, dated August 21, 1866; antedated August 2, 1866.

To all whom it may concern:

Be it known that I, JACOB DREISÖRNER, of New York, in the county and State of New York, have invented a new and useful Hydraulic-Pressure Engine; and I do hereby declare that the following is a full, clear, and exact description of the construction and operation of the same, reference being had to the annexed drawings, making part of this specification, and to the letters of reference marked thereon.

The nature of this invention consists in the arrangement of two circular disks or pistons rotating backward and forward, and placed upon the same shaft in suitable cylinders. One of these pistons is constructed with a concentric groove or cavity in its periphery, which is divided by a partition, against the one or the other side of which, in combination with a stationary wedge fitting perfectly tight in said concentric groove, a pressure of water or fluid is made to act alternately, so as to rotate said piston first in one direction and then in the opposite direction, making each time not quite one revolution. By the rotation of this piston the second piston, fast to the same shaft, is moved in the same direction. This second piston is constructed with a groove or cavity in its periphery or circumference, running spirally, similar to a screw, of any desired pitch, and closed at each end. In this spiral groove a block or small piston is fitted tightly, and held stationary from revolving with the piston by means of slides or friction-rollers working in a groove cut horizontally and longitudinally in the cylinder, whereby, while this piston-block will be prevented from turning with the piston, sufficient motion will be allowed to the same longitudinal or sidewise, corresponding to the inclination of the spiral of the groove. Both ends of this spiral groove are provided with channel-ways communicating with the heads of the cylinder and with a channel-way made in the central part of the shaft. These passages or channel-ways are closed by self-acting valves opening from the cylinder-heads into this spiral groove, to allow the water or fluid to run or be drawn into said spiral groove from a reservoir placed above this cylinder, and connected with the cylinder-heads and with valves opening from the ends of the spiral groove into the channel-way through the

central part of the shaft, to allow the water to be forced out again from said spiral grooves. The end of the shaft passes through or into a box, with the central part of which the channel-way through the shaft has a free communication, and said box is again connected with a strong and perfectly tight pressure-box, into which the water or fluid forced out of the spiral groove passes, producing thereby a pressure in said pressure-box, which is used to drive the first-mentioned piston in the manner above described, while any surplus pressure in said box may be used to drive a rotary engine, or for any other purpose which may be desired.

Figure I, Sheet I, represents a vertical longitudinal section of my machine. Fig. II, Sheet I, represents a horizontal section of the same. Fig. III, Sheet I, shows an outside view of the driving-cylinder and valve-chest, showing the arrangement of working the slide-valve. Fig. IV, Sheet II, is a cross-section of the same. Fig. V, Sheet II, is a top view of part of the driving-piston, showing the packing-rings on the sides of the concentric groove and the packing-plates in the partition-piece. Fig. VI, Sheet II, is a section through the slide-valve case, showing the ports into the cylinder. Fig. VII, Sheet II, represents a cross-section of the force cylinder and piston. Fig. VIII, Sheet II, represents part of a top view of the second or force piston, showing the packing-rings on the sides of the spiral groove and the packing-plates in the ends of the groove. Fig. IX, Sheet II, shows a top view of the piston-block working in the spiral groove. Fig. X, Sheet II, represents a section of the grooves and of the packing-rings on the sides of the grooves.

Similar letters represent similar parts.

In the accompanying drawings, A represents a shaft, near one end of which a circular disk or piston, B, is securely fastened, working in a cylinder, C, provided at one side with suitable ports *a* and *b*, to admit the water or fluid, and likewise a side port or passage, *c*, for the water to escape after having been used. These ports *a*, *b*, and *c* are covered by a suitable slide-valve, S, arranged in a casing, W, in the usual manner.

The slide-valve case W is connected, through a pipe, Y, with the pressure-box Z, and to the end of the passage *c* a pipe, *d*, is connected, to conduct the escaping water or fluid into a

reservoir, D, (see Fig. I,) situated above the cylinder E.

The circular disk or piston B is made with a groove or cavity, F, in its periphery, concentric with the motion of said piston. This concentric groove F is divided by a partition, J. (See Figs. IV and V, Sheet II.)

The piston B is provided with packing-rings on each side of the concentric groove F, to prevent any escape of water or fluid, and for the same purpose the partition J is provided with packing-plates, the construction of which will be hereinafter described.

In the cylinder C a wedge piece or block, G, is arranged between the ports or passages *a* and *b*, fitting perfectly water-tight into this concentric groove F, and forced tight into the same by means of india-rubber or other suitable springs, *f*, placed behind said wedge. (See Figs. II and IV.) By the partition J, fast to the piston B, and this stationary wedge-block G in the cylinder and working in the concentric groove F, said groove will be divided in two parts.

Upon the shaft A a second circular disk or piston, H, is arranged and firmly secured or attached to said shaft, and working in a cylinder, E, provided with suitable heads K K', which are provided with stuffing-boxes, through which the shaft A passes perfectly water-tight, and which said stuffing-boxes may partly support the shaft. Above this cylinder E a reservoir, D, is arranged, communicating through the passages *g* and *g'* with the ends of the inside of the cylinder E. This piston H is made with a groove or cavity, L, cut in its periphery and running spirally with the motion of the piston, similar to a screw-thread. The length of this spiral groove is a little less than the circumference of the piston, and the ends of this spiral groove are provided with packing-plates, and on the sides of said groove are likewise packing-rings, arranged to prevent any escape of water or fluid out of the spiral groove, the construction of which will be hereinafter described.

The shaft A, from the place where the piston H is situated to within a short distance of its extreme other end, is made hollow, so as to form a channel-way or passage, M.

In the piston H passage-ways are arranged from each end of the spiral groove L, communicating with one end of the cylinder and with this hollow part or passage M in the central part of the shaft A. The passages communicating between the ends of the spiral groove L and the cylinder-heads are closed by self-acting valves N N', (see Fig. II,) opening inward or toward the spiral groove L, and the passages between the ends of the spiral groove L and the channel-way or passage M through the shaft are closed by self-acting valves P and P', opening toward the passage M. (See Figs. I and II.)

The outer end of the shaft A passes through suitable stuffing-boxes, through a chamber, R, with the central part of which the channel-

way or passage M has a perfectly free communication by means of the openings *m m*. This chamber R is connected with a strong and perfectly tight pressure-box, Z, with a self-acting valve, T, placed at any convenient position in the connecting pipe or branch between the chamber R and pressure-box Z, said valve opening outward or into the box Z. (See Fig. II.)

Into the spiral groove L a block or piston, Q, is fitted perfectly water-tight. The upper end of this piston-block Q is provided with slides or friction-rollers *w*, fitting and working in a groove, *h*, made longitudinally in the cylinder E. By this arrangement the block Q will be held nearly stationary when the piston H is made to revolve by means of the slides or friction-rollers *w* working in the groove *h* in the cylinder, and is only capable of a slight motion sidewise or longitudinal with the cylinder, corresponding to the inclination of the spiral groove L, and accommodating itself always to the position of the spiral groove.

The manner of packing the sides of the concentric groove F and of the spiral groove L is shown in Figs. I and II, and in an enlarged size in Figs. IV and VIII, as well as in an enlarged section in Fig. X, where *p p'* represent the metal packing rings or bands. These packing-rings *p p'* on the sides of the concentric groove F form a regular circular ring, and may be joined at their ends and overlap each other, (see Fig. IV,) similar to the metallic packing-rings at present in use in steam-pistons. The rings or bands *p p'* on the sides of the spiral groove L must be made of the same spiral form as the groove L, and are made a little longer, so as to pass each other. (See Figs. II and VIII.) These metal rings are inserted into the piston diagonally to its surface about at an angle of forty-five degrees, more or less. Below these rings india-rubber or other suitable springs, *r r'*, (see Fig. X,) are placed, to press these metallic packing-rings outward against the inner surface of their respective cylinders. By this arrangement of placing the metallic rings *p p'* diagonally to the surface, a broad working-surface is obtained on the face, while the side next to the groove in which the pressure is contained presents only a sharp point or edge, against which the said pressure of the water or fluid in the grooves will have no action or hold.

The upper surface of the partition J in the concentric groove F and the ends of the spiral groove L is packed tight by an arrangement of packing-plates, *n* and *x x*, with india-rubber or other suitable springs placed below the same, to force said plates outward against the surface of the cylinder. Between the plates *x x* india-rubber or other suitable springs, *v*, are placed, to force said packing-plates *x x* at the same time sidewise, and prevent thereby any escape of water in those parts.

In the same manner the upper surface of the piston-block Q is packed, (see Fig. IX,) where *q* and *q' q'* represent the packing-plates,

and t the spring between the ends of the plates q', q' to force the same sidewise, springs, as above mentioned, being placed below said packing-plates to press the same upward. The lower and end surfaces of said piston-block Q are supposed to be ground perfectly watertight into the spiral groove L; but the same may be packed in the same manner.

The slide-valve S, whereby the water or fluid is made to pass either through the port a or through the port b , is operated by means of the ball-lever u turning on a fixed center, c . Against the side of the slide-valve case W a sliding bar, k , is arranged, having an arm, y , projecting toward the center of the piston B. On the upper end of this sliding bar k two arms, 3 3, are attached, between which the arm of the ball-lever is held. On the slide-valve rod 4 two similar arms, 2 2, are placed, one on each side of the arm of the ball-lever.

To the piston B two projecting pins, 5 and 8, are fastened. When the piston B has been turned nearly around, the pin 5 will come in contact with the lower side of the arm y , lifting thereby the same, as well as the sliding bar k , and consequently moving the ball-lever u so as to bring the ball on the top of said lever past the perpendicular center line, when the weight of the same will cause the lever u to fall suddenly backward, and lift thereby the slide-valve so as to open the lower port, b . When the piston B has turned around in the opposite direction nearly as far as required, the pin 8 will come in contact with the upper side of the arm y , pushing the same downward until the ball at the end of the lever u has again passed the center line, when the same will fall in the other direction, and move thereby the slide-valve downward so as to open the port a for the admittance of the water or fluid.

On the top of the pressure-box Z a safety-valve will be arranged with the escape-pipe leading into the reservoir D, to bring any excess of water back again into said reservoir.

Instead of placing the two pistons B and H upon one and the same shaft, which, if circumstances will allow, I consider the most preferable, each piston may be placed on a separate shaft, when said shafts must be connected together by means of suitable gearing.

The self-acting valves which I employ are made with a sharp or pointed edge as valve-seat, whereby the pressure on both sides of the valve will be nearly equalized.

The operation of the machine is as follows: Into the pressure-box Z water or any other fluid is forced, either by hand or any known mechanical means, until sufficient pressure is therein obtained to turn the piston B. The reservoir D is likewise filled with the same liquid. The piston B being in the position represented in Fig. IV, with the partition J a little above the stationary wedge G and the slide-valve S in a position to allow the water or fluid to enter through the port a , this liquid will enter through said port into that part of the concentric groove between the top of the

wedge G and the partition J, exerting its pressure against the partition J as the wedge G is held fast in the cylindrical case C in such a manner as to turn thereby the piston B around its axis in the direction indicated by the arrow. The water or fluid which is contained in the other part of this concentric groove F, between the opposite side of the partition J and the under side of the wedge G, escapes through the port b and passage c into the pipe d , and from there back into the reservoir D. This motion given to the piston B by the pressure of the water or fluid out of the pressure-box Z is communicated through the shaft A to the piston H, turning thereby said piston H in the same direction. During this motion of the piston H the end 13 of the spiral groove L will be moved away from the piston-block Q, held fast in the groove h in the cylinder E, creating a vacuum, in consequence of which the weight of the water or fluid in the reservoir will force the valve N open and gradually fill that part of this spiral groove L moving away from the piston-block Q. At the same time the water or fluid which was on the opposite side of the piston-block Q in this spiral groove L will be gradually forced out of said groove at its end 15 through the valve P' into the hollow part of M of the shaft A, and from there through the openings $m m$, chamber R, and valve T into the pressure-box Z.

When the piston B has made nearly one revolution and the partition J in the concentric groove F in said piston has moved nearly toward the under side of the block G the position of the slide-valve S is suddenly reversed in the manner above described, whereby the lower port, b , will be opened, and the water or fluid out of the pressure-box Z made to enter now below the stationary wedge or block G, acting therefore now upon the opposite side of this partition J, so as to turn the piston B in the contrary direction, and during which time the water or fluid which has acted before on the other side of said partition escapes now through the port a and through the passage c and pipe d into the reservoir D. This reversed motion of the piston B is likewise communicated to the piston H, causing thereby the end 15 of the spiral groove L to move away from the piston-block Q, while the end 13 of said spiral groove will move toward said block Q, in consequence of which water or fluid will now be drawn from the reservoir D through the valve N' into the end 15 of the spiral groove L, while the water or fluid which was drawn into said groove at its end 13 through the valve N by the last operation will now be forced out at this end 13 through the valve P into the channel-way or passage M in the central part of the shaft A, and from there through the openings $m m$, chamber R, and valve T into the pressure-box Z.

The area of the concentric groove F being considerable smaller than the area of the spiral groove L, more water will be forced into the pressure-box Z than will be required or

taken away from said pressure-box Z for the purpose of propelling or turning the piston B, in consequence of which the pressure in said pressure-box will gradually increase if not used for some other purpose, and the excess of pressure will escape through a safety-valve placed on the top of this pressure-box Z, and pass then back again into the reservoir D.

This excess of pressure or of water or fluid may be used for the purpose of driving a rotating or reciprocating engine, or for any other purpose desired.

What I claim as my invention, and desire to secure by Letters Patent, is—

1. The arrangement of a revolving piston having a concentric groove in its circumference, divided by a partition, and placed in a suitable cylinder provided with a slide-valve and a stationary wedge, (between the two parts,) made to work perfectly tight in said concentric groove, in combination with a second revolving piston placed in a suitable cylinder and provided with a spiral groove in its circumference, in which a piston-block held by said cylinder is made to move perfectly tight, said spiral groove communicating at each end through passages closed by self-acting valves with the ends or heads of the cylinder, as well as with a central passage provided in the shaft and communicating with a pressure-box connected with the slide-valve case of the first-mentioned cylinder, the whole being combined together and operating in such a manner that the piston with the spiral groove shall force water or other fluid into said pressure-box, so as to produce a pressure therein, which said pressure shall act upon either the one or the other side of the partition in the concentric groove in the first-mentioned piston in such a manner as to rotate said piston backward and forward around its axis, and which said motion shall be communicated to the second piston, operating the same in the manner specified.

2. The construction of the revolving piston B, arranged with a concentric groove, F, in its circumference, having a partition, J, and placed in a cylindrical case, C, provided with a suitable slide-valve and case, in combination with a stationary block, G, fitting tight in said groove F, and held fast in the cylindrical case C, and situated between the ports *a* and *b*, the whole being arranged and combined in the manner and for the purpose described.

3. The construction of the revolving piston

H, provided with a spiral groove, L, in its circumference, working in a cylinder, E, and arranged with suitable passages closed by self-acting valves N N' and P P', forming communications between the ends of said spiral groove L and the ends or heads K K' of the cylinder, and the reservoir D, connected with said cylinder, as well as with the passage M, made in the shaft A, and through the same and its connecting-chamber R and valve T with a strong box or chamber, Z, and operating in combination with the piston-block Q, made to fit tight in said spiral groove L, and held fast in a groove, *h*, in the cylinder E, in the manner and for the purpose substantially as set forth and described.

4. The arrangement of the channel-way M in the shaft A, communicating with the ends of the spiral groove L in the piston H, and through the chamber R and valve T with the pressure-box Z, when constructed in the manner as specified.

5. The arrangement and construction of the piston-block Q, provided with suitable packing and fitting tight in the spiral groove L, and held fast by means of slides or friction-rollers working in the groove *h*, made in the cylinder E, capable of a motion sidewise or longitudinal with the cylinder, and operating, in combination with the spiral groove L, in the manner and for the purpose substantially as described.

6. The construction of the packing rings or bands *p p'* on the sides of the concentric and spiral grooves, acting diagonally toward the grooves and to the surface of the piston, and operated by suitable springs, and arranged in the manner and for the purpose set forth.

7. The manner of packing the surfaces at the ends of the spiral groove L, as well as the surface in the partition J in the concentric groove F, by means of plates *x x* and *n*, operated by suitable springs situated below said plates, as well as by springs *v*, acting against the ends of the packing-plates *x x*, in the manner and for the purpose described.

8. The arrangement of a piston, B, provided with a concentric groove, F, and a piston, H, provided with a spiral groove, L, situated upon the same shaft, or its equivalent, and working in suitable cylinders, in the manner and for the purpose substantially as set forth and described.
